UNITED STATES PATENT OFFICE.

LOUIS LEONHARDT, OF ST. LOUIS, MISSOURI.

AUTOMATIC PRESSURE-REGULATOR FOR SODA-FOUNTAINS OF BOTTLING-MACHINES.

SPECIFICATION forming part of Letters Patent No. 367,645, dated August 2, 1887.

Application filed December 27, 1886. Serial No. 222,671. (No model.)

To all whom it may concern:

Be it known that I, LOUIS LEONHARDT, a subject of the Emperor of Germany, and a resident of the city of St. Louis, in the State of Missouri, have invented certain new and useful Improvements in Pressure-Regulators for Soda-Fountains for Bottling-Machines, of which the following is a specification.

This invention specially relates to bottling-machines wherein a constant and like pressure is required to force the liquid into the bottles; and the object of my invention is to automatically regulate and keep up the required pressure in the fountains at all times during the bottling therefrom, the pressure being derived from a generator, as usual.

The improvements consist, first, in the construction and arrangement of pipes, valves, and a spring to form an improved device, which is placed as an intermediate between the generator and fountain, the compressed air or gas being regulated to give the desired pressure by passing through this device from the generator before passing into the fountain, and, secondly, in the construction of detail parts, all of which will hereinafter fully appear and be claimed.

To more fully describe my invention, and to enable others to fully understand the same, reference is had to the accompanying drawings, in which—

Figure 1 is a side view of my improved pressure-regulator. Fig. 2 is a vertical section of Fig. 1.

A is a pipe which supports the regulator-top of the soda-fountain, and by which communication is established between both. On top of the pipe A is placed a hollow metal cup, B, preferably of the shape shown in the drawings. This cup B is made in two halves, held together by bolts and nuts passing through the annular rims of both halves. Between the rims is placed a rubber diaphragm, b, which divides the cup into two compartments or chambers, b' and b'.

C is a coil-spring placed in the upper compartment, b', and rests on the rubber diaphragm. The object of this coil-spring is to relieve the diaphragm of the strain from below and to strengthen it. This spring may, however, be dispensed with, as the same is not absolutely necessary, except where very great pressure is wanted in the fountain. On top of the spring,

or if same is not used, then on top of the diaphragm, is a stem, D, having a circular disk, d, below, which covers the largest portion of the area of the diaphragm. The stem is secured to the diaphragm by a nut, d', below, and its upper end passes through the top of the cup to the outside. On top of the stem is a nut, d", which may be raised or lowered by turning it, and serves to regulate the diaphragm to act at any pressure desired, by allowing it to rise more or less before acting on the valve-lever E, the long arm of which passes over the stem and nut, and is raised thereby as the diaphragm is raised. This lever E is fulcrumed at to the frame of the regulator or any other convenient part of same. The short arm of the lever is pivoted to a vertical stem, f, of a valve, F. This valve F is a rubber diaphragm placed in a valve-chamber or cup, F', similar in construction to the cup B, already described, and divides same into two compartments or chambers, f' and f''. The valve-stem f passes through the valve and is held to it by a nut, f''. A disk-head, f', which forms part of the valve-stem itself, or is secured to it, spreads over the top of the valve to strengthen it. The valve opens and closes the opening of the pipe G, communicating from the lower compartment, f'', out through the bottom of same to the pipe A, which communicates with the cup B and fountain. A pipe, H, connects the lower valve-chamber, f'', with the generator. The compressed air or gas from the generator passing through the pipe H into the valve-chamber f'' by its pressure raises the valve F, which opens the pipe G below it, allowing the compressed air or gas to enter into and pass through it to the fountain, until the desired pressure is reached in said fountain, when the diaphragm b is raised by the excess pressure, raising the stem and long arm of the lever E, which in turn, through the short arm, presses down the valve-stem and valve and closes the opening of the pipe G, cutting off the supply of air or gas from the generator to the fountain. As soon as the pressure in the fountain diminishes by the drawing off of its contents, the diaphragm and stem drop, relieving the lever and releasing the valve, when the pressure under the latter raises it, and the action is repeated.

To balance the valve F, or nearly so, and so

that the same can be made to open and close by the diaphragm with as little pressure as possible over and above that required in the fountain, I provide a similar cup, I, with a diaphragm, i , and place same somewhat above the valve-cup in a vertical line with same, and support it by a yoke or frame, J. The diaphragm divides the cup I into two compartments or chambers, i' and i'' , and is bolted 5 to a stem, k, by the nut k' . This stem k has a flanged head, k^2 , resting against the under side of the diaphragm, and a seat, i^3 , limits the movement of the diaphragm and stem upward. The stem extends out through the bottom of 10 the lower chamber i'' of the cup, and has a bore, k^3 , in its lower end, into which the upper end, f^6 , of the valve-stem enters. A spiral spring, L, surrounds the joining ends of both stems and rests on a collar, f^6 , of the valve-stem. 15 A nut, k^4 , on the lower end of the stem k sets over the spring, which is tensioned more or less by turning the nut up or down. This spring is thus tensioned to correspond with the pressure desired in the fountain. The upper chamber, i' , of the cup I communicates by 20 a pipe, H', with the generator, or the pipes H and H' are preferably made one and communicate with the generator. Thus the pressure top of the diaphragm i , of the upper cup, I, is 25 the same as the pressure up against the bottom of the valve F, and the valve is balanced. The spring L and nut d^2 of the stem D being set to the same pressure required in the fountain, the action of closing and opening 30 of the pipe G by the valve is instantly effected as the pressure in the fountain varies, and the action of the regulator is automatic. 35

This regulator may be used for various other purposes, where a certain pressure is constantly required to be maintained, whether a 40 gas, air, steam, or water pressure.

M is a gage, connected to the pipe A, for showing the pressure contained in the fountain.

What I claim is—

1. As an improved pressure-regulator, the 45 combination and arrangement of the cups B, F', and I, provided with their respective diaphragms b, F, and i , and connected with the pipes A, G, and H, stem D, lever E, and stems f and k, and spring L, substantially as herein 50 shown and described; and for the purpose set forth.

2. In a pressure-regulator, the balanced valve consisting of two diaphragms, F and i , within their respective cups F' and I, and a 55 tensioning-spring, L, connecting the ends of the respective stems f and k of the diaphragms F and i , in combination with the pipes H and H', connecting with the generator, and the pipes G and A, communicating with the fountain 60 and cup B, the latter being provided with the diaphragm b, connected by a stem, D, having the adjusting-nut d^2 and operating on the lever E to raise or lower the lower diaphragm F of the balanced valve to open and close the 65 pipe G; substantially as and for the purpose set forth.

LOUIS LEONHARDT.
